1

Latin name: *Malus domestica*.
Variety denomination: 'PremA093'.

BACKGROUND OF THE VARIETY

The new apple tree variety 'PremA093' was created in the course of a planned breeding program carried out at Havelock North, New Zealand. 'PremA093' originated as a result of a controlled cross made in 2001 of 'Scifresh' (seed parent, U.S. Plant Pat. No. 13,888) and 'A080R12T094' (pollen parent, not patented). 'PremA093' was selected as a single plant from among a population of seedlings derived from the parents, and was initially selected for its intense red skin color and early maturity as compared to 'Galaxy' Gala (U.S. Plant Pat. No. 6,955). The variety has been observed over a number of asexually propagated generations, and has been found to remain true to type.

'PremA093' is easily distinguished from late-maturing male parent 'A080R12T094', the fruit of which is yellow-green with little to no blush overcolor as compared to the intense red skin color of 'PremA093'. The male parent produces globose conical fruit as compared to the ovoid to conical fruit of 'PremA093'. 'PremA093' is distinguished from female parent 'Scifresh' and from similar varieties 'Galaxy' Gala and 'PremA280' (U.S. Plant Pat. No. 19,762) as set forth in Table 1 below.

TABLE 1

Comparison of 'PremA093' to female parent and other varieties				
	'PremA093'	'Scifresh'	'Galaxy'	'PremA280'
Maturity date	Very early	Mid-season	Early	Early
Pattern of skin color	Solid flush	Striped	Striped	Striped
Overcolor	Red-purple	Red with greyed-red stripes	Cherry red	Greyed-red
Flavor acidity	Sweet/acid	Sweet/medium	Sweet/mild	Sweet/mild

(57) ABSTRACT

A new and distinct apple tree named 'PremA093', the fruit of which is notable for its intense red skin color and early maturity.

5 Drawing Sheets**2****BRIEF DESCRIPTION OF THE PHOTOGRAPHS**

The attached photographs were taken at Napier, New Zealand in 2020, of 5-year-old trees and their fruit. The trees 5 were grown on 'M116' rootstock (U.S. Plant Pat. No. 18,618).

FIG. 1 shows the fruit, branches and leaves of the variety; FIG. 2 shows a stem-end view of fruit of the variety; FIG. 3 shows a calyx-end view of fruit of the variety; FIG. 4 shows a side view of fruit of the variety; and FIG. 5 shows leaves of the variety.

DETAILED BOTANICAL DESCRIPTION OF THE VARIETY

The following-detailed botanical description is based on 15 observations of 5-year-old trees made during the 2019-2020 growing season at Napier, New Zealand, except where otherwise noted. The described trees were grown on 'M116' rootstock. All colors are described according to The Royal 20 Horticultural Society Colour Chart. It should be understood that the characteristics described will vary somewhat depending upon cultural practices and climatic conditions, and will vary with location and season. Quantified measurements are expressed as an average of measurements taken 25 from a number of individual plants of the new variety. The measurements of any individual plant or any group of plants of the new variety may vary from the stated average.

Tree:

Vigor.—Moderate.

Type.—Ramified.

Habit.—Spreading.

Height.—2.4 to 3 meters.

Spread.—1.5 m.

Trunk diameter (at 30 cm above the graft).—50 to 74 cm.

Bark color.—Brown N200C.

Bark texture.—Smooth.

<i>Lenticel length.</i> —2 mm to 5 mm.		<i>Stigma color.</i> —Yellow 3C.
<i>Lenticel width.</i> —0.8 to 1.0 mm.		<i>Style diameter.</i> —1 mm.
<i>Lenticel height.</i> —Flush to slightly raised.		<i>Style color.</i> —Yellow 2D.
<i>Lenticel shape.</i> —Elongated.	5	<i>Ovary diameter.</i> —5 mm.
<i>Lenticel color.</i> —Grey-brown 199C.		<i>Ovary length.</i> —7 mm.
<i>Lenticel density.</i> —Dense, about 3 per cm ² .		<i>Ovary color.</i> —Green 141B.
Branch (fruiting branches located at around 1 m above the graft union):		Stamens:
<i>Length.</i> —1 to 1.3 meters.		<i>Quantity.</i> —14.
<i>Diameter.</i> —23 to 30 mm.	10	<i>Anther length.</i> —2 mm.
<i>Bark color.</i> —Brown N200C.		<i>Anther width.</i> —1 mm.
<i>Bark texture.</i> —Smooth.		<i>Anther color.</i> —Yellow 6D.
<i>Branch lenticel length.</i> —2 to 3 mm.		<i>Filament length.</i> —7 mm.
<i>Branch lenticel width.</i> —0.5 to 0.8 mm.		<i>Filament color.</i> —Yellow 2D.
<i>Lenticel height.</i> —Flush to slightly raised.	15	<i>Pollen.</i> —Moderately abundant, yellow 6D.
<i>Branch lenticel shape.</i> —Elongated.		Pedicel:
<i>Branch lenticel color.</i> —Grey-brown 199C.		<i>Length.</i> —24 mm.
<i>Branch lenticel density.</i> —3 to 5 per cm ² .		<i>Diameter.</i> —2 mm.
One year old shoot:		<i>Texture.</i> —Smooth.
<i>Length.</i> —15 to 30 cm.	20	<i>Color.</i> —Yellow-green 145B.
<i>Diameter.</i> —4 to 5 mm.		Sepals:
<i>Color.</i> —Brown 200A.		<i>Quantity.</i> —5.
<i>Pubescence.</i> —Light.		<i>Length.</i> —10 mm.
<i>Internode length.</i> —2.3 to 2.7 mm.	25	<i>Width.</i> —3 mm.
<i>Shoot lenticel length.</i> —0.5 to 1 mm.		<i>Shape.</i> —Pointed.
<i>Shoot lenticel width.</i> —0.5 mm.		<i>Margin.</i> —Smooth.
<i>Shoot lenticel height.</i> —Flush.		<i>Texture of upper surface.</i> —Smooth.
<i>Shoot lenticel shape.</i> —Oval.		<i>Texture of lower surface.</i> —Smooth.
<i>Shoot lenticel color.</i> —Grey 201B.	30	<i>Color of upper surface.</i> —Yellow-green 145A.
<i>Shoot lenticel density.</i> —3 to 7 per cm ² .		<i>Color of lower surface.</i> —Yellow-green 145B.
Flower buds (bud and bloom observations recorded near Yakima, Wash., USA):		Leaves:
<i>Number per spur.</i> —4 to 5.		<i>Shape.</i> —Ovate.
<i>Shape.</i> —Elongated with pointed apex.	35	<i>Length.</i> —90 to 100 mm.
<i>Length.</i> —12 mm.		<i>Width.</i> —47 to 52 mm.
<i>Diameter.</i> —8 mm.		<i>Length/width ratio.</i> —2:1.
<i>Texture.</i> —Smooth.		<i>Blade margin.</i> —Crenate.
<i>Color.</i> —Red-purple 58B.	40	<i>Apex.</i> —Acuminate.
Flowers:		<i>Base shape.</i> —Equilateral.
<i>First bloom.</i> —Early, April 16 (2021 growing season).		<i>Texture of upper surface.</i> —Glabrous.
<i>Full bloom.</i> —Early, April 20 (2021 growing season).		<i>Texture of lower surface.</i> —Glabrous with prominent veins.
<i>Pollination requirement.</i> —Required.	45	<i>Color of upper surface.</i> —Green 137A.
<i>Quantity per cluster.</i> —4 to 5.		<i>Color of lower surface.</i> —Green 138B.
<i>Diameter.</i> —45 mm.		<i>Attitude in relation to shoot.</i> —Upward.
<i>Depth.</i> —2 mm.		Petiole:
<i>Fragrance.</i> —Fragrant, typical.	50	<i>Length.</i> —30 to 41 mm.
Petals:		<i>Diameter.</i> —1.8 to 1.9 mm.
<i>Quantity per flower.</i> —5.		<i>Color.</i> —Green 137C.
<i>Length.</i> —20 mm.		Fruit:
<i>Width.</i> —17 mm.	55	<i>Quantity per cluster.</i> —4.
<i>Shape.</i> —Oval.		<i>Diameter.</i> —68 to 79 mm.
<i>Apex.</i> —Pointed.		<i>Height.</i> —72 to 82 mm.
<i>Base.</i> —Rounded.		<i>Weight.</i> —140 to 243 g.
<i>Margin.</i> —Smooth.		<i>General shape in profile.</i> —Conic to ovoid.
<i>Texture of upper surface.</i> —Smooth.		<i>Position of maximum diameter.</i> —At or above equator.
<i>Texture of lower surface.</i> —Smooth to mildly rugulose.		<i>Ribbing.</i> —None.
<i>Color of upper surface.</i> —White N155C with red-purple N57D.		<i>Crowning at calyx end.</i> —Slight.
<i>Color of lower surface.</i> —White N155B with red-purple N57C.	60	<i>Size of eye.</i> —Small.
Pistils:		<i>Aperture of eye.</i> —Partially to fully open.
<i>Quantity.</i> —3 to 4.		<i>Depth of eye basin.</i> —5.7 to 7.1 mm.
<i>Length.</i> —7 mm.		<i>Width of eye basin.</i> —24 to 26 mm.
<i>Color.</i> —Yellow 1D.	65	<i>Length of sepal.</i> —4 to 6 mm.
<i>Stigma diameter.</i> —1 mm.		<i>Bloom of skin.</i> —Light.
		<i>Greasiness of skin.</i> —Light.
		<i>Background color of skin.</i> —Yellow 11C.

US PP33,654 P2

5

Amount of over color.—95% to 100%.
Over color of skin.—Red-purple 59A and 59B.
Intensity of over color.—Intense.
Pattern of over color.—Solid flush.
Amount of russet around stalk cavity.—Low.
Amount of russet on cheeks.—None.
Area of russet around eye basin.—Low.
Length of stalk.—19 to 21 mm.
Thickness of stalk.—2.1 to 4 mm.
Depth of stalk cavity.—13 to 14.5 mm.
Width of stalk cavity.—24 to 38 mm.
Stalk color.—Greyed-orange 175B.
Firmness of flesh.—Firm.
Flesh texture.—Fine.
Aroma.—Slight.
Juiciness.—Juicy.
Brix.—12.6 to 13.1° Brix.
Flesh color.—White 155A.
Quantity of locules.—5.
Aperture of locules.—Closed to slightly open.

6

Seeds:
Quantity per fruit.—10.
Shape.—Teardrop.
Length.—9.0 to 9.6 mm.
Width.—5.1 to 6.0 mm.
Color.—Greyed-orange 175A.

5 Harvest:
Time for harvest.—Beginning February 1; 8 to 15 days before, ‘Galaxy’ (2018, Hawkes Bay, NZ).
Harvest yield.—About 31 kg per tree.
10 Number of picks.—Two.
Disease susceptibility.—Moderately susceptible to fire blight.
15 Storage characteristics.—Slow cooling after harvest prevents soft scald.
Market use.—Fresh local market and export.
Eating quality.—Very good.

I claim:
1. A new and distinct apple tree substantially as described and illustrated herein.
